corporation of Ohio

Application September 22, 1944, Serial No. 555,262

6 Claims. (Cl. 51—281)

1

This invention relates to the grinding of contours and the method of crush forming the grinding wheel employed in the grinding operation to provide an unusually long crushing roll life.

One object resides in the method of truing a grinding wheel to impart a desired irregular form including ridges and valleys, by a crushing operation applied by a rotatable crushing roll so as to form the grinding wheel with no portion of the operative surface of the wheel at an angle closer than several degrees to a radial line, but with the diameters at opposite ends of the wheel equalized to a large extent.

Another object resides in the method of shaping an end portion of an elongated workpiece having an area to be ground that is generally at a large angle to the axis of the piece, the relative positioning of the axes of the piece and the grinding wheel being so coordinated with the ridges and valleys formed in the grinding wheel that the operative face of the grinding wheel is generally at only a small angle to the axis so that the crushing roll with which the grinding wheel is formed will have a very long life.

Another object resides in the method of shaping the peripheral portion of a grinding wheel to provide a desired form including ridges and valleys, in which the grinding wheel is operated in peripheral engagement with a rotatable crushing roll and in which the grinding wheel, before the crushing operation takes place, is first soaked in a lubricant while the wheel is stationary so that the lubricant will be absorbed into the pores and applied through the grinding wheel to the area engaged by the crushing roll.

Other objects and advantages of the invention will be apparent from the following description, the appended claims, and the accompanying drawing, in which

Fig. 1 is an elevational view illustrating the method and the crushing roll embodying the present invention, the grinding wheel being illustrated in central section;

Fig. 2 is a sectional view illustrating how the workpiece is held with respect to the grinding wheel, showing a portion of the grinding wheel in central section;

Fig. 3 shows a radial section through the grinding wheel operating in conjunction with a crushing roll of a somewhat modified form;

Fig. 4 illustrates how the workpiece is held with respect to the grinding wheel corresponding to Fig. 3; and

Fig. 5 is a perspective view of a surface grinder embodying a crushing roll and a grinding wheel,

2

and in which the method of this invention may be carried out.

Referring more particularly to the drawing, and first with respect to the form of construction illustrated in Figs. 1, 2 and 5, 10 designates the grinding wheel of a grinding machine. As shown in Fig. 1, the grinding wheel may be supported on a rotatable carrying shaft 11 by suitable holding plates 12 and 13 fixed against rotation on the shaft and clamping opposite sides of the grinding wheel between them. The shaft 11 may be carried in a bearing housing 14 forming a part of the grinding machine structure 15 which includes a horizontally movable table 16 providing a support for a work holder 17 of any suitable character. Reference 18 illustrates a workpiece arranged in the holder so that the area to be ground is in line with the plane of rotation of the grinding wheel 10. Suitable means are provided for reciprocating the table back and forth below the grinding wheel, and for raising and lowering the grinding wheel as desired and as is customary in surface grinding machines.

This invention is particularly concerned with 25 the forming or truing of a grinding wheel to impart suitable ridges and valleys to the peripheral or operative surface of the wheel so that a desired irregular form is imparted to the workpiece by moving the workpiece in contact and with respect to the rotatable grinding wheel and thus 30 forming the workpiece to the desired surface formation. Fig. 2 shows one form of workpiece 18, which may be of substantial length in the direction of its axis 21 and having an area extending 35 between the points 22 and 23 that is to be ground to form ridges and valleys of the desired shape. These ridges and valleys may, for example, form a retaining head by means of which the workpiece may be eventually supported in 40 the mounting means. The length of the ground area in a direction at right angles to the plane of the section of Fig. 2 may be as long or as short as desired.

The grinding wheel at its opposite ends is of 45 approximately the same diameter, the mean or average diameter at one end of the grinding wheel thus approximating the mean diameter at the other end of the wheel, throughout its operative grinding area, the ridges and valleys imparted to the grinding wheel being so formed in its peripheral surface that the grinding wheel is intended to operate on the workpiece with the workpiece axis inclined so that the ground area on the workpiece generally lies in a plane that 55 approximates parallelism to the grinding wheel

axis. The degree to which the axis of the work-piece should be tilted depends upon two main factors in order to obtain long life of the metallic crushing roll with which the surface of the grinding wheel is formed, and long grinding wheel life, as will be presently described.

The grinding wheel is formed, to give it the desired shape, by operating it in peripheral pressure engagement with a rotatable crushing roll 25, see Fig. 1. This crusher roll may be mounted for free rotation about its own axis and may be carried by a suitable shaft 26 held in a supporting bracket 27 on the table 16 of the surface grinder, or it may be suitably held in that portion of the surface grinder that carries the grinding wheel and be arranged for movement towards and from the grinding wheel under suitable control so that it may be brought into and out of crushing operation as occasion requires. The crushing roll, as shown, is rotatable about an axis that is parallel to the grinding wheel axis, and is preferably an annularly continuous steel body having a smooth peripheral surface ground or otherwise suitably formed to provide ridges and valleys which are the same in sectional shape as the ridges and valleys to be formed on the ground portion of the workpiece. Thus the crushing roll has an irregular form in which different portions of the roll are at different angles to lines radial of the roll, providing ridges 28 and 29 between which is a valley 30, while another valley 31 is provided on the other side of the ridge 29. It will be noted that the diametrical measurements at one end of the effective surface of the crushing roll have a mean or average measurement that is about the same as at the other end of the effective surface of the roll, although this gives a grinding wheel shape that requires the workpiece axis to be held at a large angle to the grinding wheel axis so as to place the area that is actually ground on the work-piece into a more nearly horizontal position, that is, into a position that more closely approximates or attains a position in parallelism to the grinding wheel axis.

It is particularly pointed out that if the work axis 21, see Fig. 2, were arranged horizontally or parallel to the grinding wheel axis the opposite sides of the grinding wheel would be relatively as shown in the dotted lines 32 and 33, 50 and the grinding wheel axis would be as indicated by the line 34. In such case, however, the side 32 of the grinding wheel would have a considerably greater diameter than the side 33, and the grinding wheel life will be determined by the radial length of the line 32. As grinding wheels are ordinarily obtainable in a cylindrical form and must then be shaped to give the desired form, a comparatively large portion would have to be removed from the shorter diameter side in a case of this sort. Furthermore, if one side of the grinding wheel were much larger in diameter than the other, and the grinding wheel were formed by a rotatable crushing roll whose axis is parallel to the grinding wheel, one end of the crushing roll would have to be very much smaller in diameter than the other end of the roll. Where there is a large difference in diameter at opposite ends of the crushing roll, that is, with a crushing roll that is generally of an accentuated cone form, the wear is very great on the crushing roll because of the relative rubbing between the grinding wheel and the crushing surface at both the large and the small ends of the crusher.

In accordance with the present invention, however, the amount of relative rubbing and wear that takes place on the crusher is minimized and the life of the crusher is greatly increased by generally equalizing the diameter at opposite ends of the crusher. This tends to equalize the diameter of both the crusher and the grinding wheel throughout their axial extent, and this equalization should take place to an extent limited by those surface portions of the crusher or the grinding wheel that are closest to a radial line. The axis 21 of the workpiece shown in Fig. 2 should thus be inclined only to the extent that brings that part or parts of the crusher that are at the greatest angle to the axis of rotation no closer than several degrees from a line radial to that axis. With a truly radial surface on the grinding wheel or on the crusher the grinding wheel would be so formed that any wear on that surface would require a considerable amount of reforming or crushing to attain the proper shape each time the wheel wears. However, if all portions of the effective grinding wheel surface are no closer than several degrees from a line radial to the grinding wheel axis, the wheel wear of those parts that operate at the greatest linear speed and perform the most of the actual grinding will control the amount that has to be taken off of the crusher in any crushing action to restore the desired form. If the surfaces of the grinding wheel that are close to a radial line are quite short in radial extent, they may be as close as from three to five degrees, although if they are of considerable radial extent, they should be from five to seven degrees away from a truly radial line so as not to cause excessive grinding wheel wear, excessive loading of the spaces between the grinding grains of the wheel, or an excessive removal of the grinding wheel surface in a crushing operation.

By tilting the axis of the workpiece so as to arrange the area to be ground at least roughly parallel to the grinding wheel axis as indicated for example in Fig. 2 and by crushing the grinding wheel with an annular crushing roll as illustrated in Fig. 1, the mean diameter of one effective portion of the crushing roll approximates the mean diameter of the other end of the roll to an extent that brings that portion or portions of the roll that are at the greatest angle to the axis of rotation of the roll no closer than several degrees from a line radial to said axis, and with this arrangement the bisector of adjacent diverging surfaces of the crushing roll are arranged at an angle to a line radial to the crushing roll axis, as indicated by the dotted line 35 in Fig. 1 although this is contradictory to past practice wherein the bisector of diverging surfaces to be ground have been arranged as far as possible in the direction of the grinding wheel radius.

After grinding an area on the upper side of the workpiece 18, the work may be retracted from the grinding wheel, inverted in its holding fixture, and another area ground on the side then uppermost, opposite the first ground area to give a symmetrical shape to the ground end of the workpiece. In the form of construction illustrated in Figs. 2 and 4, the ground end of the work-piece is cylindrical, partly ground in one grinding operation and finished in the second after the piece is inverted. With the workpiece axis inclined to a considerable angle with respect to the grinding wheel axis, the portion of the grinding wheel that is effective on the cylindrical end portion will come down a little past the axis of sym-

metry of the workpiece to insure a complete smooth form at the very end of the workpiece, and this is accomplished without having the surface on the grinding wheel that is effective on the end of the workpiece any closer to a radial line than the several degrees previously mentioned.

Before the grinding wheel is first crushed it is first soaked in lubricant while the grinding wheel is not in rotation. This is done to minimize the possibility of the wheel breaking while being crushed and also to minimize the wear on the crushing roll and to provide a better crushing action on the grinding wheel. This is preferably accomplished by submerging the grinding wheel flat in a container of suitable lubricating oil in which the grinding wheel is held long enough to permit absorption of the oil into the pores of the wheel throughout the body of the wheel. The wheel is then placed in position on the shaft 11, the crusher is properly positioned against the grinding wheel and the two wheels are then started by driving one or the other or both so they will operate at substantially the same peripheral speed, pressure being maintained between the two rolls by feeding one towards the other during the crushing operation. The grinding wheel will thus be crushed away by the pressure action at the nip of the rolls until the grinding wheel surface attains a shape which is complementary to the shape of the crusher roll. During this crushing action, it has been found that the oil that was absorbed by the grinding wheel is as a kind of bonding agent to hold the abrasive particles together and prevent wheel breakage. During the crushing action the oil will be thrown out gradually to the surface of the grinding wheel where its bonding action is most needed. It is also applied to the effective surface of the crushing roll to reduce wear. This outward travel of the oil during the crushing operation will be produced by centrifugal force which, however, is not excessive enough to immediately dissipate all of the oil, since the grinding wheel is rotated at a comparatively slow speed as compared to that used during the actual grinding operation. In crushing, the speed of rotation of either the crushing roll or the grinding wheel may be of the order of three hundred feet per minute.

In the embodiment of the invention illustrated in Figs. 3 and 4, the grinding wheel 36, which operates about an axis 37, is provided with an irregular surface forming ridges and valleys, the grinding wheel being formed or shaped by crushing roll 38 operable about an axis 39, as the two members are rotated in peripheral pressure engagement with one another in the same manner that has been previously described. The crushing roll is provided with ridges 40, 41, 42 and 43, and valleys 44, 45 and 46, the bisectors of diverging surfaces of the crushing roll being inclined to lines radial of the crushing roll to whatever extent may be required in so arranging the sectional form of the grinding wheel at a small angle to the grinding wheel axis. The form given to the crusher is such that the left hand end of the crushing roll as viewed in Fig. 3 does not exceed the mean diameter at the other end of the roll to any substantially greater extent than is required by the angularity of the most steeply inclined surface portions on the crushing roll. The mean diameter of the smaller end of the roll approximates the mean diameter at the other end of the roll to an extent that brings those por-

tions that are at the greatest angle no closer than several degrees from a line radial to the roll axis. Such a limiting angle surface is illustrated by the portions of the crushing roll contained in the dotted lines 48 and 49. Line 49 contains only a short portion in radial depth, and consequently, the line 49 may be at an angle of from three to five degrees to the radial. The line 48, however, contains a crushing wheel surface that is of considerably greater radial extent, and this line should be at an angle no closer to the radial line than five to seven degrees to give satisfactorily long life to both grinding wheel and the crushing roll. If the sectional form of the peripheral surface of the grinding wheel were tilted counterclockwise several degrees with respect to the axis of the grinding wheel that would provide a greater equalization in the mean diameter at different portions along the length of the crushing roll and in the mean diameter at different points along the axial length of the grinding wheel and thus give better crushing roll life, but if this were done, that would make the line 48 substantially coincide with a radial line, preventing satisfactory operation of the grinding wheel over any extended period of time. Consequently, the mean diameter of the smaller end of the crushing roll only approximates the mean diameter at the left hand end of the roll as illustrated in Fig. 3 to such extent as to bring the most steeply inclined portion to from three to seven degrees from a radial line depending upon the radial length of the most steeply inclined portion.

Fig. 4 illustrates the grinding operation performed by the grinding wheel 36 on a workpiece 50 whose longitudinal axis 51 is arranged at a large angle to the axis of rotation of the grinding wheel. Here the general plane of this zone to be ground on the work is indicated by the line 53, and this is inclined only about twelve degrees with respect to the grinding wheel axis although the angularity between the ground area as represented by the mean line 53 is about forty degrees to the longitudinal axis of the workpiece. Here it will be noted that the inclined angle between the ground area on the upper side of the work and the general mean line 54 of the ground surface which may be imparted to the other side of the workpiece after turning the workpiece upside down on the holding fixture is nearly a right angle, although the relative slope between the upper and lower sides of the crusher roll 38 that has formed the grinding wheel is only about twenty-four degrees. If the grinding wheel were so arranged as to grind the same surface form on the workpiece 50 with the workpiece arranged so that its longitudinal axis 51 is parallel to the grinding wheel axis, obviously one side of the grinding wheel would be very much smaller in diameter than the other side and the effective surface of the crusher wheel used to form such a surface would have a corresponding large inclination with respect to its own axis and this would produce excessive wear on the crushing roll in the crushing operation. In accordance with the method and by use of the crusher of this invention, however, the crusher roll life is greatly increased. The grinding wheel life is also increased because of the increase in the radial length of the side of shorter diameter.

The forms of construction herein illustrated and described have been chosen as two examples of many insofar as concerns the actual shape or

formation of the crushing roll and the grinding wheel, and it is to be understood that various modifications and adaptations of the invention may be made within the spirit and scope of the appended claims.

What is claimed is:

1. The method of shaping the end portion of an elongated workpiece to provide a ground surface of a desired irregular form including ridges and valleys, and in which the area thus ground is generally at a large angle to the axis of said piece, which comprises locating said piece with respect to a grinding wheel so that the axis of the piece is at a large angle to the axis of the grinding wheel, forming the peripheral surface of the grinding wheel by a crushing roll having ridges and valleys corresponding in shape to the ridges and valleys to be imparted to the piece but with the ridges and valleys of the roll forming an area at a small angle to the axis of the roll as compared to the large angle between the axis of the workpiece and the area ground on the workpiece, the mean diameter of one end of the effective portion of the roll approximating the mean diameter at the other end of the roll to an extent that brings that portion or portions of the roll that are at the greatest angle to the roll axis no closer than several degrees from a line radial to the roll axis, and grinding the workpiece with the grinding wheel while the workpiece is so located.

2. The method of shaping the end portion of an elongated workpiece to provide a ground surface of a desired irregular form including ridges and valleys, and in which the area thus ground is generally at a large angle to the axis of said piece, which comprises locating said piece with respect to a grinding wheel so that the axis of the piece is at a large angle to the axis of the grinding wheel, crushing the peripheral surface of the grinding wheel to form ridges and valleys corresponding in shape to the ridges and valleys to be imparted to the piece but with the ridges and valleys of the wheel forming an area at a small angle to the axis of the wheel as compared to the large angle between the axis of the workpiece and the area ground on the workpiece, and in such crushing operation forming the mean diameter of one end of the effective portion of the wheel approximately to the mean diameter at the other end of the wheel to an extent that brings that portion of the wheel that is at the greatest angle to the wheel axis several degrees from a line radial of the wheel, and grinding the workpiece with the grinding wheel.

3. The method of shaping the peripheral portion of a grinding wheel to provide a desired irregular form including ridges and valleys which comprises soaking the wheel while stationary in a lubricant and then running the wheel in peripheral contact and pressure engagement with

a crushing roll to form the ridges and valleys in the grinding wheel, forming the mean diameter at one end of the grinding wheel approximately to the mean diameter at the other end of the grinding wheel to an extent that brings that portion or portions of the wheel at the greatest angle to a line several degrees from a line radial to the wheel axis.

4. The method of shaping the peripheral portion of a grinding wheel to provide a desired irregular form including ridges and valleys which comprises soaking the wheel in a lubricant until the lubricant is absorbed into the body of the wheel, then operating the wheel in peripheral pressure engagement with a crusher roll operating at substantially the same peripheral speed.

5. The method of shaping the peripheral portion of a grinding wheel to provide a desired irregular form including ridges and valleys which comprises soaking the wheel in a lubricant until the lubricant is absorbed into the body of the wheel, bringing the periphery of the wheel into engagement with a crusher roll while the wheel and roll are at rest, then operating the wheel in peripheral pressure engagement with the crusher roll operating at substantially the same peripheral speed, and with the surface speed of the wheel reduced below normal grinding speed, and maintaining the pressure until the grinding wheel is formed complementary to the cross sectional form of the crusher roll.

6. The method of shaping the peripheral portion of a grinding wheel to provide a desired irregular form including ridges and valleys which comprises soaking the wheel in a lubricant until the lubricant is absorbed into the body of the wheel, then operating the wheel in peripheral pressure engagement with a crusher roll operating at substantially the same peripheral speed, with the roll axis parallel to the grinding wheel axis, the roll having its mean diameter at one end approximating the mean diameter at its other end to such extent that the portion or portions of the grinding wheel formed by the crusher roll at the greatest angle to the grinding wheel axis are no closer than several degrees from a line radial to the grinding wheel axis.
